HYDRODYNAMIC MACHINE

Walter Ferris, Milwaukee, and James K. Douglas, Shorewood, Wis., assignors to The Oilgear Company, Milwaukee, Wis., a corporation of Wisconsin

Application August 8, 1945, Serial No. 609,584

12 Claims. (Cl. 103—161)

1

This invention relates to hydrodynamic machines of the type having a rotatable cylinder barrel, pistons and cylinders extending into the cylinder barrel from the circumferential periphery thereof and a thrust member arranged around the cylinder barrel in engagement with the outer ends of the pistons, the thrust member being eccentric to the cylinder barrel when the machine is performing useful work.

Such a machine will function as a pump when it is driven mechanically or it will function as a motor when it is supplied with liquid under pressure. In order to simplify the following explanation of the invention, the machine will be referred to herein as a pump but it is to be understood that a machine embodying the invention will also function as a motor and that designating the machine as a pump in no way limits the invention to a pump.

When a pump of this type is driven mechanically and its thrust member is eccentric to the cylinder barrel, each piston will move outward and draw liquid into its cylinder during one half-revolution of the cylinder barrel and it will be forced inward by the thrust member and expel liquid from its cylinder during the other half-revolution of the cylinder barrel.

Pumping forces are thus transmitted from the thrust member through the inward moving pistons to the liquid in the cylinders thereof, and these forces act upon the cylinder barrel and tend to move it at right angles to its axis of rotation, thereby imposing a heavy load upon the bearings which support the cylinder barrel. These bearings must thus be large enough to rotatably support the cylinder barrel when pump pressure and consequently the pumping forces are maximum. The large size of the cylinder barrel bearings and the loads imposed thereon by the pumping forces causes considerable bearing losses in the prior pumps and also causes the over all dimensions and weights of the prior pumps to be greater than would be necessary if the bearings and bearing loads were smaller.

The present invention has as an object to provide a construction in which the loads imposed upon the cylinder barrel bearings are reduced to a minimum.

Another object is to provide a construction in which the cylinder barrel is substantially hydrostatically supported and balanced.

A machine constructed according to the invention has the advantage that it may be smaller and lighter than a prior machine of the same type

2

and capacity and has a higher mechanical efficiency.

Other objects and advantages will appear from the following description of an embodiment of the invention shown somewhat diagrammatically in the accompanying drawings in which the views are as follows:

Fig. 1 is a sectional plan view of a pump in which the invention is embodied, the view being taken on the line 1—1 of Fig. 2.

Fig. 2 is a transverse section taken on the irregular line 2—2 of Fig. 1.

Fig. 3 is a transverse section taken on a line 3—3 of Fig. 1.

Fig. 4 is a section through one of the two valves which control the flow of liquid to and from the cylinders, the view being taken on the line 4—4 of Fig. 3.

Fig. 5 is a section through the same valve taken on the irregular line 5—5 of Fig. 4.

Fig. 6 is in part a force diagram and in part a vertical section through the operating mechanism of the pump, the section being taken on the line 6—6 of Fig. 3 and the cylinder barrel being rotated slightly from the position shown in Fig. 1.

Fig. 7 is a force diagram and represents an end view of the cylinder barrel and the thrust members.

The pump chosen for illustration has its pistons and cylinders arranged in a cylinder barrel 1 and divided into two sets each of which consists of a suitable number of pistons and cylinders depending upon the volumetric capacity of the pump. As shown, two circumferential rows of radial cylinders 2 are formed in the front half of cylinder barrel 1, a piston 3 is fitted in each cylinder 2, two circumferential rows of radial cylinders 4 are formed in the rear half of cylinder barrel 1 and a piston 5 is fitted in each cylinder 4. The total displacement of all of the pistons 5 is preferably the same as the total displacement of all of the pistons 3. Also, each cylinder 4 is preferably diametrically opposite a cylinder 2 but in a different plane.

Liquid flows to and from the cylinders through a plurality of axial channels 6 and 7 which extend inward from opposite ends of cylinder barrel 1 and each channel may connect with one or more cylinders. As shown, each channel 6 extends inward from the front end of cylinder barrel 1 into communication with a cylinder 2 in each of the two front rows, and each channel 7 extends inward from the rear end of cylinder barrel 1 into communication with a cylinder 4 in each of the two rear rows.

Cylinder barrel 1 is rotatably supported by bearings 8 and 9 within a casting 10 or suitable construction. For the purpose of illustration, casing 10 has been shown as having formed integral therewith a front distributing block 11 and a rear distributing block 12 through which liquid flows to and from the pump cylinders. Rotation of cylinder barrel 1 is effected by means of a drive shaft 13 which is splined thereto and extends outward through block 11 in which it is rotatably supported by a bearing 14.

Pistons 3 and 5 are adapted to be reciprocated, respectively, by two thrust members 15 and 16 which encircle cylinder barrel 1 and which have their axes offset from the cylinder barrel axis when the pump is pumping liquid. For the purpose of illustration, the pump has been shown as being of the rolling piston type disclosed in Patent No. 2,704,068. That is, the inner peripheral surface of each thrust member is inclined in opposite directions and the outer ends of the pistons are beveled so that each piston engages the inner surface of a thrust ring upon a single spot which is offset far enough from the piston axis to cause the piston to rotate in its cylinder as it reciprocates therein.

In order that thrust members 15 and 16 may be rotated in unison with cylinder barrel, they are mounted, respectively, in two bearings 17 and 18 which have been shown as ball bearings. If the pump is to be of the constant displacement type, the outer races of bearings 17 and 18 are fixed in stationary positions within casings 10 but they have been shown as being fixed, respectively, within two slide blocks 19 and 20 which may be shifted in opposite directions transversely of the cylinder barrel axis to vary pump displacement.

Slide block 19 is mounted between roller or ball bearings 21 and 22 which ride upon bearing surfaces arranged upon the upper and lower walls of casing 10 and which permit slide block 19 to be freely moved transversely of the cylinder barrel axis but restrain it from vertical movement. Slide block 20 is similarly mounted between bearings not shown. Slide blocks 19 and 20 are prevented from moving axially by casing 10 such as by having their adjacent faces in engagement with a spacer ring 23 and their outer faces in engagement, respectively, with opposed bearing surfaces 24 and 25 formed on the inside of casing 10.

Any suitable means may be employed to shift slide blocks 19 and 20. As shown, a lever 26 has an actuator 27 formed upon its inner end and pivoted upon its center-line to casing 10 by a pin 28. Actuator 27 has two slots 29 and 30 extending inward from its opposite ends in alignment with each other and with pin 28. One end of actuator 27 extends between two spaced apart lugs 31 which are fixed to or formed integral with slide blocks 19, and the other end of actuator 27 extends between two spaced apart lugs 32 which are fixed to or formed integral with slide block 20. Two pins 33 and 34 are fixed, respectively, in lugs 31 and 32 equidistant from pin 28 and are closely fitted in slots 29 and 30 respectively.

The arrangement is such that, when lever 26 is in its neutral position, the axes of thrust members 15 and 16 coincide with the axis of cylinder barrel 1 and pump displacement is zero. When lever 26 is moved in one direction or the other from its neutral position, actuator 27 will shift slide blocks 19 and 20 the same distance in op-

posite directions simultaneously and the pump will deliver liquid in a direction and at a rate determined by the direction and extent of movement of lever 26.

In order to maintain the over all length of the pump at a minimum, cylinder barrel 1 has been shown as having its ends recessed and channels 6 and 7 terminating within the recesses. The recessed end portions of cylinder barrel 1 are made flat and smooth to form valve seats for two identical valves 40 and 40^a which cooperate with channels 6 and 7 to control the flow of liquid to and from cylinders 2 and 4. Valve 40 is arranged between the front end of cylinder barrel 1 and distributing block 11, and valve 40^a is arranged between the rear end of cylinder barrel 1 and distributing block 12. Each valve has been shown as an integral structure but it may be formed by separate pieces welded or otherwise fastened together.

Valve 40 is provided with a central opening of sufficient size to permit shaft 13 to pass freely therethrough and to permit valve 40 to be properly adjusted to its seat on the end of cylinder barrel 1. The inner end or face of valve 40 has formed therein two diametrically opposed substantially crescent shaped ports 41 and 42 with which each channel 6 communicates alternately as cylinder barrel 1 rotates, the outer ends of channel 6 constituting cylinder ports which cooperate with valve ports 41 and 42 to control the flow of liquid to and from cylinders 2, all of the cylinder ports being of the same length.

The portions of the valve face between adjacent ends of ports 41 and 42 cooperate with the end of cylinder barrel 1 to provide seals between the two valve ports. In practice, the number and size of the cylinders in each row and the number and size of channels 6 are such that the length of each cylinder port, that is the angular distance across the outer end of each channel 6, is equal to or slightly less than the angular distance between adjacent ends of valve ports 41 and 42 so that, during rotation of cylinder barrel 1, each channel 6 opens to one valve port substantially instantaneously after it moves out of communication with the other valve port.

The means for connecting valve ports 41 and 42 to an external circuit and the means for holding valves 40 and 40^a against the ends of cylinder barrel 1 may be similar to those shown in application Serial No. 485,279, filed May 1, 1943, to which reference may be had for specific arrangements. As shown, valve port 41 communicates with a chamber 43 which is formed within valve 40 and has two passages 44 leading therefrom through the rear face of valve 40. Also, valve port 42 communicates with a chamber 45 which is formed within valve 40 and has two passages 46 leading therefrom to the rear face of valve 40, only one passage 46 being shown.

Distributing block 11 has been shown as having two hold-up motors 50 arranged therein above the horizontal center-line of valve 40 and two hold-up motors 51 arranged therein below the horizontal center-line of valve 40 but the number of hold-up motors may be varied.

Each passage 44 communicates with a cylinder 52 of a hold-up motor 50 and each passage 46 communicates with a cylinder 53 of a hold-up motor 51. The two cylinders 52 are connected to each other by a passage 54 which extends outward through distributing block 11 for connection to one side of an external circuit, and two cylin-

ders 53 are connected to each other by a passage 55 which extends outward through block 11 for connection to the other side of the circuit.

The four hold-up motors 50 and 51 are identical and each has a hollow piston 56 fitted in its cylinder and urged by a spring 57 against an annular sealing member 58 which is urged by spring 57 against the outer end of valve 40, the contacting surfaces of member 58 and valve 40 being ground flat and the contacting surfaces of piston 56 and member 58 being ground spherical to provide self aligning liquid tight seals therebetween. The openings through pistons 56 and member 58 provide communication between the passages in the valve and the inner ends of the hold-up cylinders so that liquid may flow freely through the valve and the distributing block to and from the external circuit.

When the pump is idle, valve 40 is held to its seat solely by springs 57, but as soon as the pump starts to deliver liquid, the pressure created by the pump acts upon the outer ends of the hold-up pistons 56 in the pressure side of the circuit and causes those pistons to urge valve 40 toward its seat with a force proportional to pump pressure.

Valve 40 may also be provided with auxiliary hold-up motors and with balancing motors as shown in application Serial No. 485,279 but such motors have been omitted from the drawing to avoid complicating the views.

Valve 40^a is identical to valve 40 and distributing block 12 is identical to distributing block 11 except that it has no central opening to accommodate a shaft. Consequently, they have not been fully illustrated and a description thereof is deemed unnecessary, like parts and passages as far as shown being indicated by like reference numerals with the exponent "a" added to the reference numerals applied to valve 40^a and distributing block 12. Passage 54 in block 11 and passage 54^a in block 12 are connected to each other by a channel 59 which is also connected to a channel 60 by means of which the machine may be connected to one side of an external circuit. Passage 55 in block 11 and passage 55^a in block 12 are connected to each other by a channel 61 which is also connected to a channel 62 by means of which the machine may be connected to the other side of an external circuit. Channels 59 and 61 have been shown as external channels but they may be arranged within the pump casing.

The pump may be supercharged by an auxiliary pump according to common practice but, since supercharging forms no part of the present invention, no auxiliary pump has been shown.

Operation

When the axes of slide blocks 19 and 20 are offset from the cylinder barrel axis as shown and cylinder barrel 1 is rotated in a clockwise direction in respect to Figs. 2 and 7, the pistons 3 in the upper half of cylinder barrel 1 will be forced progressively inward by thrust member 15 and will eject liquid from their cylinders through the channels 6 connected thereto, valve port 41, chamber 43, passages 44, hold-up motors 50 and passage 54 into channel 59, and the pistons 3 in the lower half of cylinder barrel 1 will move progressively outward and draw liquid into their cylinders through the channels 6 connected thereto, valve port 42, chamber 45, passages 46, hold-up motors 51 and passage 55 from channel 61.

At the time, the pistons 3 in the lower half of cylinder barrel 1 will be forced progressively

inward by thrust member 16 and will eject liquid from their cylinders 4 into channel 59 and the pistons 3 in the upper half of cylinder barrel 1 will move progressively outward and draw liquid into their cylinders 4 from channel 61. Since the axes of thrust members 15 and 16 are offset equal distances from the axis of cylinder barrel 1, the stroke of each piston 3 will be the same as the stroke of the opposite piston 5.

When the liquid discharged by the pump meets a resistance, pump pressure rises and thrust members 15 and 16 must force pistons 3 and 5 inward against the pressure in their cylinders. Thrust member 15 transmits a pumping force F (Fig. 7) through each piston 3 to the liquid in its cylinder and thrust member 16 transmits a pumping force F^a through each piston 5 to the liquid in its cylinder.

Each force F is equal in magnitude and opposite in direction to a force F^a but in the prior pumps of this general type all of the pumping forces are transmitted through the pistons in only one half of the cylinder barrel and the reaction to the pumping forces must be provided solely by the cylinder barrel bearings which must be large enough to carry the heavy loads imposed thereon.

The resultant of forces F and the resultant of forces F^a oscillate from one side to the other of the vertical center-line of the cylinder barrel as rotation of the cylinder barrel causes successive channels 6 and 7 to move into and out of communication with the valve ports but the average or mean position of each resultant is on the vertical center-line of the cylinder barrel. For all practical purposes therefore, the pumping forces transmitted from thrust member 15 through pistons 3 may be considered as concentrated in a single downward force F¹ (Fig. 7) located on the vertical center-line of the cylinder barrel, and the pumping forces transmitted from thrust member 16 through pistons 5 may be considered as concentrated in a single upward force F^{1a} located upon the vertical center-line of the cylinder barrel.

Forces F¹ and F^{1a} are equal in magnitude and opposite in direction and would cancel each other if they were in the same plane but, as indicated in Fig. 6, they are offset from each other so that force F¹ tends to impose a heavy downward load upon bearing 8 and force F^{1a} tends to impose a heavy upward load upon bearing 9. That is, forces F¹ and F^{1a} tend to rotate cylinder barrel 1 in a vertical plane.

At the same time, pump pressure acts upon the pistons 56 of hold-up motors 50 (Figs. 3 and 4) in distributing block 11 and causes them to urge valve 40 toward cylinder barrel 1. The forces exerted by these two pistons may be considered as being concentrated into a single force F² which is located midway between the two pistons and is therefore located upon the vertical center-line of cylinder barrel 1 above the horizontal center-line thereof. Force F² is at all times proportional to force F¹ for the reason that each of these forces is proportional to pump pressure.

Since valve 40^a is identical to valve 40 and since the hold-up motors in distributing block 12 are identical to and function in the same manner as the hold-up motors in distributing block 11, the hold-up motors in distributing block 12 exert upon valve 40^a a hold-up force F² (Fig. 6) which is equal in magnitude and opposite in direction to hold-up force F² and which is located upon the vertical center-line of cylinder barrel 1 and spaced

below the horizontal center-line thereof the same distance that force F_2 is spaced thereabove.

As indicated in Fig. 6, hold-up forces F_2 and F_2^* act at right angles to pumping forces F_1 and F_1^* and resist rotation of cylinder barrel 1 in a vertical plane by forces F_1 and F_1^* . The resultant R of forces F_1 and F_2 passes through a point located upon the cylinder barrel axis midway between pistons 3 and 5 and the resultant R^* of forces F_1^* and F_2^* passes through the same point.

Since forces F_1 and F_1^* are equal in magnitude and opposite in direction and since forces F_2 and F_2^* are also equal in magnitude and opposite in direction, resultants R and R^* are equal in magnitude and opposite in direction so that, theoretically, no pumping force is transmitted to the cylinder barrel bearings which, theoretically, need to be only large enough to carry the weight of the cylinder barrel. The cylinder barrel bearing losses are thus very small and the small size of the cylinder barrel bearings make possible the production of a pump which is considerably smaller and lighter than the prior pumps of the same general type and capacity.

The machine embodying the invention has been described as a pump but the machine will function as a motor when supplied with motive liquid and the term "pump" as used in the specification and claims is intended to mean a hydrodynamic machine regardless of whether the machine functions as a pump or as a motor.

The invention herein set forth is susceptible of various modifications without departing from the scope of the invention which is hereby claimed as follows:

1. In a hydrodynamic machine, the combination of a rotatable cylinder barrel having a first and a second set of cylinders extending inward from its circumferential periphery and a first and a second set of channels extending inward from its opposite ends into communication with the cylinders of said first and second sets respectively, a piston arranged in each cylinder, a thrust member extending around said cylinder barrel and engaging the outer ends of the pistons of one set, a second thrust member extending around said cylinder barrel and engaging the outer ends of the pistons of the other set, the axes of said thrust members being offset in opposite directions from the cylinder barrel axis, two valves arranged upon opposite ends of said cylinder barrel to control the flow of liquid to and from said cylinders, each valve having a high pressure port and a low pressure port with which each channel in the adjacent end of said cylinder barrel registers alternately as said cylinder barrel rotates, and means for urging each of said valves against said cylinder barrel with a force which varies in accordance with variations in the pressure in its high pressure port.

2. In a hydrodynamic machine, the combination of a rotatable cylinder barrel having a first and a second set of cylinders extending inward from its circumferential periphery and a first and a second set of channels extending inward from its opposite ends into communication with the cylinders of said first and second sets respectively, a piston arranged in each cylinder, a thrust member extending around said cylinder barrel and engaging the outer ends of the pistons of one set, a second thrust member extending around said cylinder barrel and engaging the outer ends of the pistons of the other set, the axes of said thrust members being offset in opposite directions from

the cylinder barrel axis, two valves arranged upon opposite ends of said cylinder barrel to control the flow of liquid to and from said cylinders, each valve having a high pressure port and a low pressure port with which each channel in the adjacent end of said cylinder barrel registers alternately as said cylinder barrel rotates, means for urging each of said valves against said cylinder barrel with a force which varies in accordance with variations in the pressure in its high pressure port, and means for shifting said thrust members in opposite directions to vary the displacement of said machine.

3. In a pump having a rotatable cylinder barrel and pistons and cylinders extending inward from the circumferential periphery of said cylinder barrel, the combination of two valves arranged upon opposite ends of said cylinder barrel for controlling the flow of liquid to and from said cylinders, two thrust members arranged around said cylinder barrel to engage the outer ends of said pistons and having their axes offset in opposite directions from the axis of said cylinder barrel so that during rotation of said cylinder barrel pistons at opposite sides of the cylinder barrel axis are moved inward simultaneously by pumping forces transmitted thereto from said thrust members and the resultants of all pumping forces tend to rotate said cylinder barrel in the plane of said resultants, and means for applying to each valve a hold-up force upon that side of the cylinder barrel axis upon which pumping forces are applied to the pistons adjacent to that valve so that the hold-up forces applied to the two valves tend to counteract the rotative effect of the pumping forces.

4. In a pump having a rotatable cylinder barrel and pistons and cylinders extending inward from the circumferential periphery of said cylinder barrel, the combination of two valves arranged upon opposite ends of said cylinder barrel for controlling the flow of liquid to and from said cylinders, two thrust members arranged around said cylinder barrel to engage the outer ends of said pistons and having their axes offset in opposite directions from the axis of said cylinder barrel so that during rotation of said cylinder barrel pistons at opposite sides of the cylinder barrel axis are moved inward simultaneously by pumping forces transmitted thereto from said thrust members and the resultants of all pumping forces tend to rotate said cylinder barrel in the plane of said resultants, means for applying to each valve a hold-up force upon that side of the cylinder barrel axis upon which pumping forces are applied to the pistons adjacent to that valve so that the hold-up forces applied to the two valves tend to counteract the rotative effect of the pumping forces, and means for shifting said thrust members in opposite directions to vary the displacement of said pump.

5. In a pump having a rotatable cylinder barrel and pistons and cylinders extending inward from the circumferential periphery of said cylinder barrel, the combination of two valves arranged upon opposite ends of said cylinder barrel for controlling the flow of liquid to and from said cylinders, two thrust members arranged around said cylinder barrel to engage the outer ends of said pistons and having their axes offset in opposite directions from the axis of said cylinder barrel so that during rotation of said cylinder barrel pistons at opposite sides of the cylinder barrel axis are moved inward simultaneously by pumping forces transmitted thereto from said thrust

member and the resultants of all pumping forces tend to rotate said cylinder barrel in the plane of said resultants, and hold-up motors energized by liquid discharged by said pump for applying to each valve a hold-up force upon that side of the cylinder barrel axis upon which pumping forces are applied to the pistons adjacent to that valve so that the hold-up forces applied to the two valves tend to counteract the rotative effect of the pumping forces.

6. In a pump having a rotatable cylinder barrel and pistons and cylinders extending inward from the circumferential periphery of said cylinder barrel, the combination of two valves arranged upon opposite ends of said cylinder barrel for controlling the flow of liquid to and from said cylinders, two thrust members arranged around said cylinder barrel to engage the outer ends of said pistons and having their axes offset in opposite directions from the axis of said cylinder barrel so that during rotation of said cylinder barrel pistons at opposite sides of the cylinder barrel axis are moved inward simultaneously by pumping forces transmitted thereto from said thrust members and the resultants of all pumping forces tend to rotate said cylinder barrel in the plane of said resultants, hold-up motors energized by liquid discharged by said pump for applying to each valve a hold-up force upon that side of the cylinder barrel axis upon which pumping forces are applied to the pistons adjacent to that valve so that the hold-up forces applied to the two valves tend to counteract the rotative effect of the pumping forces, and means for shifting said thrust members in opposite directions simultaneously to vary the displacement of said pump.

7. In a pump, the combination of a rotatable cylinder barrel having a first set of substantially radial cylinders arranged adjacent one end thereof and a second set of substantially radial cylinders arranged adjacent the other end thereof and fluid channels extending inward from each of its ends into communication with the cylinders of the adjacent set, a piston fitted in each cylinder, a valve arranged upon each end of said cylinder barrel to control the flow of liquid to and from the cylinders of the adjacent set and having a high pressure port and a low pressure port with which each channel in the adjacent end of said cylinder barrel registers alternately as said cylinder barrel rotates, a thrust member extending around said cylinder barrel to engage the outer ends of the pistons in the first set of cylinders, a second thrust member extending around said cylinder barrel to engage the outer ends of the pistons in the second set of cylinders, the axes of said thrust members being offset in opposite directions from the cylinder barrel axis so that during rotation of said cylinder barrel pistons at opposite sides of and adjacent opposite ends of said cylinder barrel are moved inward simultaneously by pumping forces transmitted thereto from said thrust members and the resultants of all of said pumping forces tend to rotate said cylinder barrel in the plane of said resultants, and means for applying to each valve a hold-up force upon that side of the cylinder barrel axis upon which pumping forces are applied to the pistons adjacent to that valve so that the hold-up forces applied to the two valves tend to counteract the rotative effect of the pumping forces.

8. In a pump, the combination of a rotatable cylinder barrel having a first set of substantially

radial cylinders arranged adjacent one end thereof and a second set of substantially radial cylinders arranged adjacent the other end thereof and fluid channels extending inward from each of its ends into communication with the cylinders of the adjacent set, a piston fitted in each cylinder, a valve arranged upon each end of said cylinder barrel to control the flow of liquid to and from the cylinders of the adjacent set and having a high pressure port and a low pressure port with which each channel in the adjacent end of said cylinder barrel registers alternately as said cylinder barrel rotates, a thrust member extending around said cylinder barrel to engage the outer ends of the pistons in the first set of cylinders, a second thrust member extending around said cylinder barrel to engage the outer ends of the pistons in the second set of cylinders, the axes of said thrust members being offset in opposite directions from the cylinder barrel axis so that during rotation of said cylinder barrel pistons at opposite sides of and adjacent opposite ends of said cylinder barrel are moved inward simultaneously by pumping forces transmitted thereto from said thrust members and the resultants of all of said pumping forces tend to rotate said cylinder barrel in the plane of said resultants, means for applying to each valve a hold-up force upon that side of the cylinder barrel axis upon which pumping forces are applied to the pistons adjacent to that valve so that the hold-up forces applied to the two valves tend to counteract the rotative effect of the pumping forces, and means for shifting said thrust members in opposite directions to vary the displacement of said pump.

9. In a pump, the combination of a rotatable cylinder barrel having a first set of substantially radial cylinders arranged adjacent one end thereof and a second set of substantially radial cylinders arranged adjacent the other end thereof and fluid channels extending inward from each of its ends into communication with the cylinders of the adjacent set, a piston fitted in each cylinder, a valve arranged upon each end of said cylinder barrel to control the flow of liquid to and from the cylinders of the adjacent set and having a high pressure port and a low pressure port with which each channel in the adjacent end of said cylinder barrel registers alternately as said cylinder barrel rotates, a thrust member extending around said cylinder barrel to engage the outer ends of the pistons in the first set of cylinders, a second thrust member extending around said cylinder barrel to engage the outer ends of the pistons in the second set of cylinders, the axes of said thrust members being offset in opposite directions from the cylinder barrel axis so that during rotation of said cylinder barrel pistons at opposite sides of and adjacent opposite ends of said cylinder barrel are moved inward simultaneously by pumping forces transmitted thereto from said thrust members and the resultants of all of said pumping forces tend to rotate said cylinder barrel in the plane of said resultants, and hydraulic means operated at a pressure proportional to the pressure created by said inward pistons for holding said valves against the ends of said cylinder barrel and for counteracting at least in part the rotative effect of said pumping forces

10. In a pump, the combination of a rotatable cylinder barrel having a first set of substantially radial cylinders arranged adjacent one end thereof and a second set of substantially radial cylinders

11

ders arranged adjacent the other end thereof and fluid channels extending inward from each of its ends into communication with the cylinders of the adjacent set, a piston fitted in each cylinder, a valve arranged upon each end of said cylinder barrel to control the flow of liquid to and from the cylinders of the adjacent set and having a high pressure port and a low pressure port with which each channel in the adjacent end of said cylinder barrel registers alternately as said cylinder barrel rotates, a thrust member extending around said cylinder barrel to engage the outer ends of the pistons in the first set of cylinders, a second thrust member extending around said cylinder barrel to engage the outer ends of the pistons in the second set of cylinders, the axes of said thrust members being offset in opposite directions from the cylinder barrel axis so that during rotation of said cylinder barrel pistons at opposite sides of and adjacent opposite ends of said cylinder barrel are moved inward simultaneously by pumping forces transmitted thereto from said thrust members and the resultants of all of said pumping forces tend to rotate said cylinder barrel in the plane of said resultants, hydraulic means operated at a pressure proportional to the pressure created by said inward moving pistons for holding said valves against the ends of said cylinder barrel and for counteracting at least in part the rotative effect of said pumping forces, and means for shifting said thrust members in opposite directions to vary the displacement of said pump.

11. In a pump, the combination of a rotatable cylinder barrel having a first set of substantially radial cylinders arranged adjacent one end thereof and a second set of substantially radial cylinders arranged adjacent the other end thereof and fluid channels extending inward from each of its ends into communication with the cylinders of the adjacent set, a piston fitted in each cylinder, a valve arranged upon each end of said cylinder barrel to control the flow of liquid to and from the cylinders of the adjacent set and having a high pressure port and a low pressure port with which each channel in the adjacent end of said cylinder barrel registers alternately as said cylinder barrel rotates, a thrust member extending around said cylinder barrel to engage the outer ends of the pistons in the first set of cylinders, a second thrust member extending around said cylinder barrel to engage the outer ends of the pistons in the second set of cylinders, the axes of said thrust members being offset in opposite directions from the cylinder barrel axis so that during rotation of said cylinder barrel pistons at opposite sides of and adjacent opposite ends of said cylinder barrel are moved inward simultaneously by pumping forces transmitted thereto from said thrust members and the re-

12

sultants of all of said pumping forces tend to rotate said cylinder barrel in the plane of said resultants, and hydraulic hold-up motors engaging said valves and communicating with said high pressure ports for holding said valves against the ends of said cylinder barrel and for counteracting at least in part the rotative effect of said pumping forces.

12. In a pump, the combination of a rotatable cylinder barrel having a first set of substantially radial cylinders arranged adjacent one end thereof and a second set of substantially radial cylinders arranged adjacent the other end thereof and fluid channels extending inward from each of its ends into communication with the cylinders of the adjacent set, a piston fitted in each cylinder, a valve arranged upon each end of said cylinder barrel to control the flow of liquid to and from the cylinders of the adjacent set and having a high pressure port and a low pressure port with which each channel in the adjacent end of said cylinder barrel registers alternately as said cylinder barrel rotates, a thrust member extending around said cylinder barrel to engage the outer ends of the pistons in the first set of cylinders, a second thrust member extending around said cylinder barrel to engage the outer ends of the pistons in the second set of cylinders, the axes of said thrust members being offset in opposite directions from the cylinder barrel axis so that during rotation of said cylinder barrel pistons at opposite sides of and adjacent opposite ends of said cylinder barrel are moved inward simultaneously by pumping forces transmitted thereto from said thrust members and the resultants of all of said pumping forces tend to rotate said cylinder barrel in the plane of said resultants, hydraulic hold-up motors engaging said valves and communicating with said high pressure ports for holding said valves against the ends of said cylinder barrel and for counteracting at least in part the rotative effect of said pumping forces, and means for shifting said thrust members in opposite directions to vary the displacement of said pump.
